2,210,887

STRAIGHTENING AND CLAMPING MECHANISM FOR BOOKING MACHINES

Joseph C. Donnelly, Barberton, Ohio, assignor to
The Diamond Match Company, New York,
N. Y., a corporation of Delaware

Application October 7, 1939, Serial No. 298,355

5 Claims.

(Cl. 93—2)

This invention relates to match booking machines, having reference more especially to a type of booking machine that is equipped with means for securing the flaps of match book covers in closed position preparatory to the discharge of the finished books. A machine of this type is illustrated in United States Patent No. 1,042,472, wherein the closing means comprises a bed or shelf upon which the match books, face upward, are imposed in succeeding order, the face of each book embodying a foldable cover flap and an end retaining fold therefor, and also a tucker member which overhangs the bed or shelf and moves in contact with and from the flap of each book in a manner to tuck the free end of the flap under the retaining fold.

The object of my invention is to provide simple and efficient book straightening and clamping means arranged in cooperative relation to the bed and the tucker member, as will be hereinafter described, the scope of the invention being expressed in the appended claims.

In the drawings—

Figure 1 is an elevation of a portion of the delivery end of a match booking machine equipped with mechanism embodying my invention, the tucker being in raised position.

Fig. 2 is a transverse section through the intermittently rotatable flap-folding wheel and the tucking mechanism of the machine, the match books being represented at succeeding flap folding and tucking stages, the tucker members being in down position upon the completion of the flap tucking operation and the vibratory book straightening and clamping members being engaged with the cover back.

Fig. 3 is a vertical section through the book-supporting bed and the vibratory straightening and clamping members, as on the line 3—3 of Fig. 2.

Fig. 4 is a rear elevation of the bed and adjuncts including the vibratory straightening and clamping members and the actuating cams therefor, said member being in retracted or unclamping position and the tucker members being raised preparatory to the discharge of the finished books.

Fig. 5 is a vertical section through a pair of vibratory spring pressed members for acting upon the adjacent inner edges of two adjoining books.

Fig. 6 is a perspective view of one of the vibratory members.

Fig. 7 is a similar view of an oscillatory frame and the cam heads thereon for periodically actu-

ating the vibratory straightening and clamping members.

Referring to the annexed drawings, 10 designates a portion of the main frame at the delivery end of a match booking machine of the type hereinbefore referred to, and 11 designates the main cam shaft extending longitudinally of the machine. 12 designates one of the links of an intermittently-movable chain of book holders from which books with outwardly-extending closure flaps are ejected in succeeding pairs by means of a plunger 13 carried by a horizontally reciprocating slide 14, which chain and slide are operated in timed relation through suitable connections with cams on the shaft 11, as usual. 15

15 designates an intermittently rotatable wheel which is mounted on the main frame adjacent the path of the book holders, and which wheel has in and around its periphery equally-spaced pairs of pockets 16 into each succeeding pair of which, in a dwell of the wheel, the ejected books are inserted by the plunger 13 with the closure flaps of the books extending outwardly from the wheel. The wheel is actuated in the usual manner. Overlying the upper semi-circular path of the wheel are spaced flap-bending members 17 which terminate in rearward resilient extensions 18 overhanging an adjacent channeled bed 19 supported by the main frame. The cover flaps of each succeeding pair of books in their intermittent travel to the extensions, are angularly flexed by the members 17, and, while the wheel is at rest, the books are endwise ejected from the pockets of the wheel and upon the bed 19 during the succeeding rearward stroke of the slide 14 by means of pushers 20 on an overhanging structure 21 carried by the slide. The extensions 18 in the passage of the books thereunder yieldingly press down the folded flaps. The books, in similar endwise and face arrangement, are discharged in pairs from the wheel 15, with the larger or headed ends of the matches leading and the folded flaps of the covers upward. 25

Overhanging the wheel 15 is a four-motion tucker arm 22 having a downwardly extending bifurcated portion 23 carrying spaced friction blocks 24 in proximity to the flaps of the respective match books which are seated in the channels of the bed. The blocks 24 by actuation of the tucker arm are effective to bear upon the 30 underlying folded cover flaps *a* of each succeeding pair of books *B* and tuck the free ends of the flaps under the retaining folds *b* at the narrow ends of the respective books. 35

Mechanism such as shown in Patent No. 55

1,042,472 may be employed to reciprocate the arm 22 lengthwise and at determined intervals to effect the rising and permit the falling motion of the arm relatively to the cover flaps; that is to say, the forward end of the arm is pivoted to the upstanding arm 25 of a lever which is fulcrumed on a stud 26 supported by the frame of the booking machine, and the depending arm 27 of the lever has a roll 28 which is fitted in the race of a face cam 29 fast on the main shaft. The means herein shown for vertically moving the tucker arm includes a lifter bar 30 having at its upper end a roll 31 upon which a suitably disposed insert 32 in the arm is normally held by means of a spring connection 33 between the arm 22 and the lifter bar. This bar has a bifurcated foot 34 that straddles a shaft 35 having its bearings in a suitably-disposed bracket 36 on the base of the main frame. The shaft 35 is driven from the main shaft 11 by suitable gearing, as 37. The foot of the bar 30 is equipped with a lateral roll 38 which is actuated by a face cam 39 fast on the shaft 35, the contour of the cam race being such as to effect the requisite vertical motion of the lifter bar and the tucker arm.

According to my invention simple and efficient means is provided to centralize the respective books on the bed with respect to the tucker members 24 immediately preceding the effective action of such members on the cover flaps of the books, and then also clamp the books to prevent their displacement during the tucking action. This means as herein shown comprises two pairs of complementary members which are movable transversely of and in clamping and unclamping relation to the longitudinal edges of the backs of the covers of the books imposed upon the bed.

In the present instance the clamping members for each book are constituted by the upper arms 40 of a pair of spaced levers of substantial width which are pivoted, as at 41, on the bed, which bed has therein openings 42 through and below which the levers extend. The tops of the upper arms project slightly above the bed and are provided with inwardly directed toes 43 which by actuation of the levers are moved toward and from the opposing edges of the back of the cover imposed on the bed and between the levers. In their inward motion the levers simultaneously bear against the respective opposing edges of the cover back in a manner to position the book centrally of the overlying tucker member 24, and at the limit of the inward motion the overhanging toes 43 bear upon the margins of the cover and clamp it firmly upon the bed. The book is thus held against displacement during the effective action of the tucker member on the cover flap. (See Fig. 3.)

The inner levers of the respective pairs are mounted on a common pivot 41 and are resiliently urged to their inward or clamping relation to the respective covers by the action of a suitable spring, such as a torsion spring 44 which encircles the pivot and has its legs bearing against the upper arms of the respective levers. Each of the outer levers has a supporting pivot and is similarly urged to clamping position by a spring 45. The two pairs of levers are simultaneously swung to unclamping positions against the action of the springs 44 and 45 by means of reciprocating bevelled cam heads 46 and 47 which are arranged in spaced relation to co-act with the lower arms 48 of the respective levers in timed relation to the tucker members 24. The central cam head 46 co-acts with the lower arms of the two inner levers, and a cam head 47 co-acts with the lower arm of

each of the outer levers. The cam heads are supported by a vibratory skeleton frame 49 which is pivotally supported, as at 50, beneath the bed by and between lugs 51 depending from the bed 19, and is also pivotally connected by a depending link 52 to an arm 53 which is fixed to the lifter bar.

When the lifter bar 30 and the tucker members 24 are elevated by the agency of the cam 39 the cam heads 46 and 47 are brought in contact with the opposing lower arms of the respective levers, thus swinging the upper arms of the levers from the cover receiving channels of the bed 19 preparatory to the entry of a pair of open match books in the channels. Then upon the entry of the books in the channels the lifter bar and tucker members are lowered. In their initial descent the cam heads escape the lower arms of the levers, thus permitting the latter to resume their normal inner positions so as to contact with and clamp the opposing edges of the backs of the book covers, (as in Fig. 3), whereupon the tucker members are brought in effective contact with the cover flaps. Upon the completion of the tucking operation the lifter bar and tucker members are raised to effect the unclamping of the books, (as in Fig. 4), and the finished books are then ejected preparatory to a repetition of the clamping and tucking operations on a succeeding pair of books supported on the bed.

I claim:

1. The combination with a support for a match book having an open cover flap and a retaining portion for the free end of the flap, and a flap tucking element having horizontal and vertical components of motion, of a book clamping means including a member mounted on said support for movement in a direction transversely of the book and against a longitudinal edge of the cover, and means for actuating said clamping member in timed relation to the said tucking element.

2. The combination with a support for a match book having an open cover flap and a retaining portion for the free end of the flap, and a flap tucking element having horizontal and vertical components of motion, of a vibratory member mounted for movement transversely of the book and having a clamping portion movable in an arc overhanging the opposing longitudinal edge of the cover back upon the support, and means for actuating said vibratory member in timed relation to said tucking element.

3. The combination with a support for a match book having an open cover flap and a retaining portion for the free end of the flap, and a flap tucking element having horizontal and vertical components of motion, of a pair of spaced levers mounted on the support to swing to and from the respective sides of the book and having at their upper ends toe portions for clamping the respective longitudinal edges of the cover back, and means for actuating said levers in timed relation to said tucking element.

4. The combination with a support for a match book having an open cover flap and a retaining portion for the free end of the flap, and means for tucking the flap in said retaining portion, said means including a flap tucking member and a reciprocating lifter bar, of a pair of vibratory members mounted to swing to and from the respective sides of the book, said vibratory members having angular toe portions to embrace the opposing longitudinal edges of the cover back and clamp it upon the support when the vibratory members are swung inward, and means under the influence of

the said lifter bar for periodically actuating said vibratory members in timed relation to the said tucking members.

5. The combination with a support for a match book having an open cover flap, of means for clamping the back of the cover upon the support, said means including a pair of spaced complementary levers mounted on the support and having at their upper ends angular toe portions to

embrace the opposing longitudinal edges of the cover back and clamp it upon the support when the levers are swung toward each other, spring means for maintaining said levers normally in clamping position, and means for periodically re-
tracting said levers against the action of the spring means. 5

JOSEPH C. DONNELLY.
